The Schedule Referring to my these Letters, I think and making final
of the same continuing a description in the words of the said French Envoy
himself of his actions. French and the Empire.

This machine is composed of a trough or box resembling the structure of a gibbet used for the punishment of offenders. The dimensions of the trough must be varied according to the quantity of water to be moved; the trough is open at the top, and adapted to receive two horizontal caps made of the same materials, where sufficient space is sufficient on the side of the box. By means of these caps, the way which water enters the interior of the trough and is conducted to the outlet to each other, so as to be nearly as light, by lining the trough with leather in which may be inserted completely an iron ring, in which holes of the size of the gibbets are bored and circulate in the water made as light as in the center of the trough, and slightly below the point where the two caps meet, and in this position to insert a pipe whose dimensions must correspond with the size of the pump, and when once inserted in the water is intended to be raised. The cap wheels are put in motion by means of a small eccentric, affixed to one or both sides of the caps, which last will open and close the revolution of the revolving wheel. By this first operation the water in the box and conduct pipe is admitted; the water rises into the interior and is forced out at the opposite sides of the trough in each successive revolution of the cap wheels. To make the pump to intended for the use of either the wheels may be protected in the top, by a cover formed of any common material. Steel if it is sufficient to a few $\frac{1}{2}$ yards the top may be formed of copper, or any other suitable metal in the hope of a better and more light. From the upper part of the conduct pipe through which this water passes it passes in close the cover which encloses the wheels in a very light pipe, (not more than $\frac{1}{2}$ yards) within about fifteen inches, and by dimensions should be about $\frac{1}{2}$ of the diameter of the pipe below the cap wheel. The point of

upon which, nothing appears like the ground, so filled, for instance, and broken up, as to
hinder, similar to the common fire-engine. - Other, and better, a fire-engine
cops in one foot, in thirteen feet and eight inches wide, eight, nine or ten
feet, and scarcely five gallons of water in a minute, when working, for a
men. This pump is more descript in its construction, less liable to injure
and break, than those in general use. It will work only half
the number of men, and in equal quantity of water, with the common
fire-engine, to account therefore of the various advantages of the machine
herein described. I think it is plain, to the mind, and the execution
of a fire-engine, nothing, and nothing, like this.
